COMBINATION REGISTER AND CONTROL MOUNT FOR AIR CONDITIONERS

James C. Hoiby and Robert L. Westrum, Minneapolis,
Minn., assignors to D. W. Onan & Sons, Inc., Minne-
apolis, Minn., a corporation of Minnesota

Application April 13, 1956, Serial No. 41,055

Term of patent 14 years

(Cl. D62—4)

Fig. 1

Fig. 2

Fig. 1 is a view in side elevation of a combination register and control mount for air conditioners embodying my new design in use on an air conditioner, the latter is shown in dotted lines for illustration; and

Fig. 2 is an enlarged face view of the combination register and control mount shown in Fig. 1.

We claim:

The ornamental design for a combination register and control mount for air conditioners, as shown and described.
